UNITED STATES PATENT OFFICE

HARRISON W. ROGERS, OF NEW YORK, N. Y.

SYNCHRONIZED SOUND AND PHOTOGRAPHY

Application filed October 31, 1928. Serial No. 316,197.

The present invention relates to improvements in synchronized sound and photography, one object of the invention being the provision of a means whereby a single or 5 what is known as a double phonograph or sound reproducing machine is connected to be operated in synchronism with either one of two motion picture projectors, the synchronizing mechanism of which is connected 10 through a clutch device to both projectors so that when one is operated the other will be operated without affecting or being affected by the other projector, thus providing a device of this character which is especially 15 adapted for use in the present projecting booths of the various entertaining establishments so that it is unnecessary to provide an individual sound reproducing unit with each projector.

20 A further object of this invention is the provision of an apparatus of this character in which the two projectors are readily controlled one at the right hand and the other at the left-hand side of the sound reproducing 25 machine, and whereby the starting of one in no way influences the starting of the other and which, in the event of both projectors being operated simultaneously, would in no way deleteriously affect the sound reproducing 30 mechanism or the synchronizers.

With the foregoing and other objects in view, which will appear as the description proceeds, the invention resides in the combination and arrangements of parts and in 35 the details of construction hereinafter described and claimed, it being understood that changes in the precise embodiment of the invention herein disclosed can be made within the scope of the claims without departing 40 from the spirit of the invention.

In the accompanying drawings:—

Figure 1 is a top plan and diagrammatic view of the complete mechanism;

Figure 2 is a detail view of one of the synchronizers;

Figure 3 is an enlarged detail view of one of the clutch mechanisms used for connecting the synchronizer operating mechanism with its respective projector; and

Figure 4 is a sectional part of one of the

sound reproducing machines with the pick-up and switch.

Figure 5 is a top plan view thereof.

Referring to the drawings, the numerals 5 and 5' designate the respective projectors 55 which are here shown as operated through the adjustable and automatic control mechanism 7 and 7'. These mechanisms as here shown are provided with the switches 8—8', so that the respective motors M² or M³ may 60 be operated, with the governors 50—50' to control and regulate the speed delivered to the projector.

Disposed between the two projectors 5—5' is a casing 10 for the double phonograph or sound reproducing mechanism, which, as here shown, is provided with the two record-carrying platforms 11, 11' and operated in such a manner that one platform is only rotated at a time, the same having its individual motor 70 M—M', controlled from the circuit, as indicated in Figure 1.

Mounted within the casing 10 are the two synchronizing devices 12 and 12', the detail construction of which is shown in Fig. 2 and 75 is particularly set forth in my co-pending application, Serial No. 316,788, filed November 2, 1928; and journaled within this casing is a shaft 13 which is adapted to operate one side of said synchronizer, while its respective 80 motor M or M' operates the opposite side.

Carried upon the opposite ends of the shaft 13 exteriorly of the casing 10 are the slideable clutch members 14 and 14' and through the means of which the respective projectors 5 or 5' will rotate the shaft 13, there being mounted upon the respective shafts 17, 17' connected to and driven from the projector mechanisms the fixed clutch member 16, 16', the detail of which is clearly shown in Figure 90 3.

The member 14, as shown in Figure 3, is provided with the teeth 15 adapted to cooperate with the teeth 15' of the member 16, and as there shown, when the shaft 17 is 95 driven by its projector 5 in the direction of the arrow, as illustrated in Figure 1, the teeth will transmit motion to the shaft 13, but should the shaft 17 be stationary, and the opposite projector rotate the shaft 13, the mem- 100

ber 14 will be slid against the action of the spring 22 upon its splined carrying member 19 which is fixed to the shaft 17 so that the shaft 17, 17' will not be affected by the operation of the opposite projector.

5 By this means an automatic engaging and releasing clutch is provided and no manual action is necessary to stop the clutch action of the projector 5' if the projector 5 is operated, or vice versa, and due to the fact that 10 the sound reproducing machine is located between the two projectors, the operator is in ready access to all members and can place the records upon the platform 11-11', and 15 manipulate the various mechanisms, so that there will be no intermission in the operation from one projector to the other.

As illustrated in Figure 1, one preferred form of circuit is shown, the magnets 22 and 23 being provided in the respective mechanisms 7 and 7' so that the synchronizer 12 or 12' will automatically manipulate the same so that either one of the motors M or M' will 20 control the speed of the motor of its respective mechanism 7 or 7' to, in turn, slow down or accelerate the speed of its respective projector. There is also provided in this circuit a film controlled switch 25-26, (as shown in my U. S. Patent No. 1,254,436, dated January 22, 1918), which, in turn, controls the electro-magnets 27 and 28 of the synchronizer for connecting and disconnecting the respective record-carrying platforms 11 or 11' to 25 operate its portion of the synchronizer, thus insuring the connection of the respective record platform at the desired time so that synchronized sound and photography can be simultaneously produced, each projector being provided with one of the film-control devices so that the sound record-carrying platforms 11-11' may be individually controlled by either projector during the rendition.

30 The circuit for controlling the electro-magnets 27 and 28 includes the selecting switch S, which connects either film controlled switch 25 or 26 for operation, and when the switch 25 is connected, the circuit includes the contact 25, the conductor 33, the switch S, the conductor 34, the magnet 27 of the platform 11 and the magnet 28 of the platform 11' (thus connecting the platform 11 with the synchronizer and disconnecting platform 11' from its synchronizer), the conductor 35, the 35 switch S, and the conductor 38. This action energizes the electro-magnet and causes the armature lock 73 to be attracted which, in turn, moves the lever 72 against its spring 74 and throws the clutch member 71 to engage 40 the clutch member 68, which, through the sleeve 69, rotates the gear 70 and its large gear 77. As the motor driven shaft of the platform 11 operates the gear 65, and also the gear 66 on the shaft 67, the gears 68 and 45 76 are rotated. Thus both gears 76 and 77

are rotated oppositely and produce with the gears 80 a differential.

As the gears 80 are mounted upon the arms 81, and such arms are connected by the sleeve 82 to the shaft 83, the circuit controlling the 70 segment 84 and the switches 85 and 85' are controlled, and as long as the speeds of the motors M' and M² are in proper predetermined speed ratio, the segment 84 is in a fixed position, but as the speed of the motor 75 M increases, the segment is biased and the switches 85 operated, as in my companion application heretofore mentioned, to regulate and control the speed, that is, accelerate or retard, the projector. This is done as here shown by energizing either one of the electro-magnets 22 or 23, the first to retard and the latter to accelerate, or vice versa, as may be desired.

The switch S' is to control the operation of the electro-magnets 22 and 23 of either projector, and when thrown to the left, places the contacts 85 in position to control those of the projector 5. Thus, to energize the electro-magnet 22 the switch 85 is closed and includes the conductor 44, the switch S', the conductor 45, the electro-magnet 22, the conductor 49, another member of the switch S, and the conductor 48; while to energize the electro-magnet 23, the switch 85' is closed and includes the conductor 44; the switch S', conductor 45, electro-magnet 23, the conductor 46, another member of the switch S, and the conductor 47.

50 In order to supply electric current to operate the motors, a generator or other source G is employed, and when the switch 8 is closed, the circuit includes the generator G, the conductor 39, the motor M², and the conductor 43, while when the switch 8' is closed, the circuit includes the generator G, the conductors 39 and 39', the motor M³ and the conductors 43' and 43.

The circuit to operate either motor M or M' is the same and both motors are run simultaneously, there being means provided for connecting and disconnecting the platforms 11 or 11', or for individually starting the motors, as may be desired, but as here shown, one circuit is as follows and includes the generator G, the conductors 39 and 40, the switch 41, the motors M and M' and the conductors 42 and 43.

55 In order that the loud speakers 58 through the conductors 57 and the amplifying panel 56 may be energized from the pick-ups P or P', and at the proper place of engagement of the stylus with the phonic groove of the record R, the swinging pick-up arm 51 or 51' 60 is employed. Each arm, as shown, is connected to the head 61 carried by the pivoted stud 30 in the base 59, said base being attached to the frame 10 and there being one to each of the turntables 11-11'. 65

A spring 62 is disposed between the head 61 upon the stud 60 so as to normally move the sleeve 63 and its arm 63' clockwise as viewed in Figure 5 and connected to but insulated from the arm is the contact 52 which, in turn, is connected to one side of the pick-up. An adjusting screw 54 is mounted in a bracket 54' fixedly attached to and insulated from the base 59 and carries a spring contact 53, to which is led a wire that connects the amplifying panel and the source 55 so that the pick-up will be connected in circuit therewith. By this means, the pick-up can be placed on the record, and as the sound rendition is to be effected, say, when the platform is revolved three revolutions, the screw 54 is adjusted to place the contact 53 so that when the pick-up and the arm with its sleeve 63 has been moved by the phonic groove, the width 20 of three grooves, the contacts 53 and 52 will engage and the amplifying circuit will be closed.

From the foregoing description, taken in connection with the drawings, it is evident that with this arrangement the operation of producing synchronized pictures is greatly reduced in that two projectors are so connected with the sound reproducing mechanisms so as not to interfere one with the other, and at the same time is provided with automatic clutching devices which permit the connecting or disconnecting automatically of the desired projector with the synchronizer supported in the casing of the sound reproducing machine, thus rendering it unnecessary for the operator to manually control the clutches or to leave one projecting machine and go to another, as is the present practice where the sound record operating member is an individual element connected to and operated adjacent to its respective projector, and, therefore, necessitating the operator to walk around from one machine to the opposite side of the other and rendering it impossible for a single operator to produce a continuous performance.

I claim:—

1. In an apparatus of the character described, the combination of two motor driven motion picture projectors, a sound reproducing machine having a driving motor, said latter machine being interposed between the two, motion picture projectors, a synchronizing device, a common shaft drive from one side thereof, two one way clutches one to each projector connecting the projectors to said shaft said clutches being of the type that when one is being driven by the projector the other clutch is free or in reverse, and means connecting the motor of the sound reproducing machine to the other side of the synchronizing device.

2. In an apparatus of the character described, two motor driven motion picture

projectors, a motor driven sound reproducing machine interposed between the two, a synchronizing device, a common shaft drive from one side thereof, and two one way clutches, one to each projector for connecting both projectors to said shaft whereby one clutch will be free while one projector is running or is operated at a greater speed than the other projector.

3. In an apparatus of the character described, two motion picture projectors, two electrical motors, one to drive each projector, manually controlled means for regulating the speed of said projectors, a sound reproducing machine interposed between the two projectors, an electric motor for driving said sound reproducing machine, a synchronizing device, a common shaft drive from one side thereof, two normally engaged clutches one at each end of said shaft and for connecting both of said projectors to said shaft and whereby said shaft can be driven by either projector, and whereby one projector at a time can be operated and operate through its means for connecting the synchronizing device with either one of the motors of the projectors, and means connecting the motor of the sound reproducing machine to the other side of the synchronizing device, whereby the speed of the motor of the operating projector is regulated by the motor of the sound reproducing machine through the synchronizing device.

In testimony whereof I affix my signature.
